CLAIM

The ornamental design for a coffee-making kit, as shown and described.

DESCRIPTION

FIG. 1 is a front perspective view of a coffee-making kit in accordance with the subject disclosure.

FIG. 2 is a rear perspective view thereof;

FIG. 3 is a bottom perspective view thereof;

FIG. 4 is a front side view thereof;

FIG. 5 is a left-side view, the right side being a mirror image thereof;

FIG. 6 is a rear view thereof;

FIG. 7 is a top view thereof;

FIG. 8 is a bottom view thereof;

FIG. 9 is a front-perspective, exploded view thereof;

FIG. 10 is a rear-perspective, exploded view thereof;

FIG. 11 is a right-side, exploded view, the left side exploded view being a mirror image thereof;

FIG. 12 is a front, exploded view thereof; and,

FIG. 13 is a rear, exploded view thereof.
